UNITED STATES PATENT OFFICE.

LEWIS HALLOCK NASH, OF SOUTH NORWALK, CONNECTICUT, ASSIGNOR TO NASH
ENGINEERING COMPANY, A CORPORATION OF NEW YORK.

TURBO-DISPLACEMENT ENGINE.

988,133.

Specification of Letters Patent. Patented Mar. 28, 1911.

Application filed December 31, 1904. Serial No. 239,071.

To all whom it may concern:

Be it known that I, LEWIS HALLOCK NASH, engineer, a citizen of the United States of America, and a resident of South Norwalk, Connecticut, have invented certain new and useful Improvements in Turbo-Displacement Engines, of which the following is a specification, illustrated by the accompanying drawings.

10 My invention is directed to improvements in motive power and consists in certain novel features of construction and operation, by which an elastic fluid, as steam or compressed air, is caused to give motive power
15 to a device.

I have shown in the drawings various forms of structures embodying my invention and in order that persons skilled in the art may be able to practice my invention, the
20 features which constitute my improvement will be described in the following specification and particularly pointed out in the claims.

In its principle of operation my invention
25 partakes of the nature of an impact or turbine engine and also of a displacement structure and I have therefore called my device a turbo-displacement engine.

I will now describe the drawings which
30 show several forms of structures having my improvement, in which:

Figure 1 represents a cross-section of a device having my improvement. Fig. 2 is a side view of one of the heads, showing the
35 ports. Fig. 3 is a longitudinal section on the line 2, 2 of Fig. 1, showing the ports and passages of the case and piston. Fig. 4 is an end view of the piston. Fig. 5 is a longitudinal section of the same. Figs. 6 and 7
40 are cross-sections showing details of the compound engine shown in Fig. 8, in which Fig. 6 is a section on the line 4, 4 of said figure, and Fig. 7 is a section on the line 3, 3, the piston being removed. Fig. 8 is a longitudinal section of a compound engine of
45 three units showing the governor and the oil supply device. Fig. 9 is a cross-section of the outlet passage on the line 5, 5 of Fig. 8.

In my improved engine I make use of a
50 liquid as a means of transmitting the power from the motive fluid to the engine. The liquid is introduced into a closure and subjected to the pressure of the motive fluid. This pressure forces the liquid through a
55 passage and it is driven upon a reaction

wheel wherein the power is utilized and the liquid is returned to its original position to repeat the cycle. These features are embodied in the structure illustrated in Figs.
1 to 5.

The case 6 is provided with the supply passage 7 and the discharge passage 8. The case 6 is closed upon the end with the cylinder heads 9, 9, which are provided with the inlet ports 10, 10, and the outlet ports 11, 11. These ports are connected with the passages 7 and 8 in the case. The passages in the heads are preferably formed to open upward, in order that the liquid that may flow into them can fall within the lower part
60 and flood the ports 10 and 11 to keep the case chamber filled with liquid to the desired point. To prevent the liquid from escaping from the exhaust, the receiving chamber 16 is constructed in the outlet passage into
65 which the exhaust from the ports may whirl about and discharge the liquid before the gaseous portions pass out of the exhaust pipe.
70

The piston of wheel 12 is mounted on the shaft 13, and operates in bearings eccentric to the case chamber so as to make a joint with one side of the case while upon the other side of the wheel a crescent shaped passage is formed between the periphery of
80 the wheel and the case walls. The wheel is provided with arms 14, which are curved at their outer ends so as to form reaction surfaces to receive the impact of the liquid. The center of the wheel is provided with
85 passages 15, which, acting with the ports 10, control the inflow of the fluid to the spaces on one side of the wheel, while upon the other side they co-act with the ports 11, 11, to control the exhaust of the working fluid.
90

Fig. 1 shows the wheel and case in one position of its operation in order to show the action of the parts. It will be seen that the port 10 (shown in dotted lines) is in communication with the passages leading to
100 the wheel spaces *y*, *z* and *o*, while the exhaust port 11 is in communication with the wheel spaces *s*, *t*, *u*, *v* and *w*. Suppose now that the wheel is revolving in the direction of the large arrow and that the case chamber is
105 filled with water to the level of the line *n*. If there were no pressure in the center of the wheel chamber, the water in the case would assume a rotating position whose level was the broken line *n*. Hence the wheel blades
110

would form a closure with the water, forming spaces surrounding the wheel, which would increase in volume on one side of the wheel while they would continually decrease in 5 volume on the other side of the wheel. In Fig. 1 the spaces z , o , p , q and r are enlarging while the spaces s , t , u , v , w are contracting and we have here present all the 10 features of a displacing structure which will make a rotary engine.

Now let us consider the device as being operated by steam pressure. The steam would be admitted through the port 10 to the space z , while the steam in the spaces 15 p , q , r , will be expanding. At the same time the spaces s , t , u , v , w , will be in communication with the exhaust port 11, from which the steam can escape into the outlet pipe. In this case we are supposing that the water 20 is revolving at the same speed as the wheel and that the pressure is not great enough to change the level of the revolving water. Suppose now that the pressure of the steam is greatly increased, then its pressure will 25 drive the water out from the spaces z , o , p , q , and r , as shown by the arrows, and this water will flow around the wheel chamber as indicated by the larger arrow at a velocity greater than that of the wheel and 30 the level of the water in these spaces would take a position such as indicated by the lines a , b , c , d , and e . This water would now flow to the other side of the wheel and would be received upon the curved arms of the 35 blades upon which it would exert a pressure in the direction of the motion of the wheel. The level of the water in the exhaust spaces under the action of centrifugal force and the inwardly directing action of 40 the blades may be indicated in a general way by the lines f , g , h , i , k , which are intended to represent the filling action of the water as it is brought to the speed of the wheel and fills the spaces. This operation 45 continues during the revolution of the wheel. A wheel space starting in the position a first passes by the port 10, from which it receives the pressure of the steam. As it passes forward the space enlarges by the 50 eccentric action of the wheel and also by the ejection of the water from the space. When the wheel blade has passed over the port 10, the steam is cut off and from there on the steam will act expansively through 55 the positions p , q , and r , until the blade reaches the position s , and the exhaust port 11 is opened, when the steam escapes into the exhaust pipe. Passing on through the 60 positions s , t , u , v and w , the steam is exhausting and the spaces are being refilled with water until in the positions x and y , the spaces are completely filled and they pass onward to complete another cycle. Considering the displacement action, therefore, it will be observed that one of the walls

of the enlarging and contracting closures is a liquid and the liquid being the moving wall constitutes the piston. 20 is a wall governor or other suitable controlling device arranged to throttle the supply of 70 steam and so control the speed of the engine. It will thus be seen that the liquid performs a cycle of operations in passing from the filled spaces, being driven through the crescent-shaped passage upon the wheel and 75 then being returned to its original position; and it will also be seen that the motive fluid also performs a cycle of operations, acting expansively in the displacement action of the engine and also in imparting motion to 80 the liquid. I have therefore called the device a two fluid motor and the steam or other prime mover may be called the motive fluid. The co-action of these fluids combines to develop power in the engine. 85

In the operation of the engine under steam pressure, there will be a certain amount of condensation of the steam and this will supply a certain amount of water to maintain the required amount for the 90 proper working of the engine, but in order that this condensation shall not be too great I may make use of a surface of oil to prevent direct contact of the steam with the water. This oil will naturally float upon the surface 95 of the water and since oil is not a good conductor of heat, and since the oil and steam will not naturally mix, the presence of the oil will, to a large extent, prevent the condensation of the steam. This oil can be 100 supplied to the engine through the steam pipe of the lubricator 22, as shown in Fig. 8, or in any other convenient manner.

It will be understood that my improved engine may be operated with other forms 105 of motive fluids, as for instance, compressed air, and that I may use any liquid in the place of water. When a powerful engine is desired I may use mercury as the driven fluid, or I may use oil for the same purpose. 110 When the engine is operating with compressed air the oil is preferred, for various reasons of a practical nature; but it is to be understood that I do not limit my invention to the use of any particular liquid. 115

In order to adapt my engine to the use of steam with high economy, or to utilize the high pressures of the motive fluid I combine the engines in series so that the exhaust from one engine is carried to the next engine and so on. By this means the work 120 of the motive fluid is distributed between several cylinders and a more perfect utilization of the force of the motive fluid can be secured. In this combination, any liquid that may escape from one case will pass into the next in series, and any gas that may have leaked from one case will be expanded in the next, and the device can be operated at a lower speed to utilize a given pressure. 125

Figs. 7 and 8 show one form of device having three power chambers in series. In this compound engine, the individual units are like that shown in Figs. 1 to 5, and the 5 exhaust port of the first in series opens into a passage leading to the inlet port of the next unit, and in these units the inlet and outlet ports are in the opposite heads. In order to show the arrangement clearly there 10 is shown a device having three engines in series, but any number of engines that may be desired can be used.

Referring to Figs. 6, 7, 8 and 9, the supply pipe is provided with a governor 20, 15 which controls the supply of the steam or other motive fluid to the engine. 22 is a lubricator of a well known form which is attached to the supply passage through the pipes 23, 24. The motive fluid enters the 20 passage 25, from which it passes through the port 29 into the wheel chamber 35. After doing its work in this chamber it passes out of the port 30 into the passage 26. This passage is shown in section in Fig. 6, 25 and it is made of an enlarged section and of such a shape that the liquid will not be carried over into the next engine, but will be separated from the fluid and will remain by gravity in the lower part of the passage, 30 and in case the spaces in the wheel chamber are not completely filled with liquid, this liquid will flow backward and supply the wheel chamber with the liquid. The motive fluid now passes through the port 31 to the 35 wheel chamber 36, and then passes through the passage 27, to the port 38, into the wheel chamber 37, and after doing its work therein it escapes through the port 34, into the discharge passage 28.

40 Without enumerating the many modifications of which this invention is capable, what I desire to secure by United States Letters Patent are the following:

1. In a turbo-displacement engine, the 45 combination of a chamber, a rotary member containing buckets within said chamber, passages being formed between the chamber and the rotary member, a liquid rotating in said chamber, means for introducing a fluid 50 under pressure to the buckets of said wheel to expel the liquid from one bucket and introduce it to another of the buckets.

2. The combination of a casing, a member 55 moving therein and provided with buckets, a liquid rotating in the casing and adapted to enter the buckets successively, and a fluid for expelling the liquid from one bucket to a succeeding bucket.

3. A turbo-displacement engine consisting 60 of a case chamber, inlet and outlet ports centrally located within said chamber, a wheel eccentrically located within said case chamber dividing said chamber into enlarging and contracting portions and turbine 65 blades upon said wheel adapted to utilize

the motion of said wheel to produce power, a liquid in the chamber adapted to enter and recede from the spaces between the blades, and means for forcing the liquid from one of said spaces against the blades and into 70 another of said spaces.

4. In a turbo-displacement engine, the combination of a wheel, turbine blades upon said wheel, said wheel and blades being eccentrically mounted within a case chamber, 75 ports centrally located within said chamber, a liquid within said chamber, a fluid admitting to said chamber by means of said ports, the opening of said ports being controlled by the position of said blades, sub- 80 stantially as set forth.

5. In combination in a two fluid engine, of a case chamber having ports in each head, a wheel operating eccentrically in said chamber, said wheel having ports at each end co-operating with the case ports to control the inlet and discharge of the motive fluid and to retain the liquid, substantially as set forth. 85

6. In a turbo-displacement engine the combination of rotating enlarging and contracting closures, one of the walls of which is composed of a liquid, ports for controlling the flow of a lighter fluid, such as air or steam, under pressure into and from said 90 closures, and a turbine structure acted upon 95 by said liquid.

7. In a turbo-displacement engine a turbine structure comprising a rotating part with enlarging and contracting closures and means for impelling a heavier fluid through 100 said turbine structure by the pressure of a lighter fluid in said closures.

8. A motor device consisting of a revolving member having closures, a liquid entering and receding from said closures, and 105 means for expelling the liquid from one closure and injecting it into another as the member turns.

9. A motor piston consisting of a system of revolving closures containing a liquid 110 body combined with means for driving said liquid from one revolving closure to another.

10. A motor piston consisting of a system of revolving closures containing a liquid 115 body combined with means for driving said liquid from one revolving closure to another, and combined with a case chamber directing the current of the liquid into said closure.

11. In a motor, the combination with a revolving member including a plurality of closures and a turbine structure, of a liquid entering and receding from said closures, and means for expelling the liquid from one closure, and forcing it in the direction of 120 rotation of said revolving member against the turbine structure and into another closure. 125

12. In a motor, the combination with a revolving member having closures, of a case 130

chamber having a passage for a liquid from one set of closures to another, and means for introducing a fluid under pressure into one of said closures to force the liquid out of 5 one of said closures through said passage and into another closure.

13. In a motor, the combination with a chamber, of a rotary member in said chamber having buckets, a liquid in said chamber and buckets, and means for forcing said liquid out of one bucket and for causing it to impinge upon another bucket.

14. In a motor, the combination with a chamber, of a rotary member in said chamber having buckets, a liquid in said chamber and buckets, and means for forcing said liquid out of one bucket and for causing it to flow in the direction of rotation of and at a greater speed than the rotary member.

15. In a motor, the combination with a chamber, of a rotary member in said chamber having buckets and having a close axial fit with said casing, a liquid in said chamber and buckets, and means for introducing a fluid into said buckets to force the liquid therefrom and exert a torque on said rotary member.

16. In a motor, the combination with a chamber, of a rotary member eccentrically placed in said chamber, and having buckets and having a close axial fit with said casing, a liquid in said chamber and buckets, and means for introducing a fluid into said buckets to force the liquid therefrom and exert a torque on said rotary member.

17. In a motor, the combination with a chamber, of a rotary member in said cham-

ber having buckets, a turbine structure, a liquid in said chamber and buckets, and a port adjacent the center of the rotary member 40 for introducing a fluid under pressure into a bucket for forcing said liquid out of a bucket and for imparting a velocity to drive the turbine structure.

18. In a motor, the combination with a 45 chamber, of a rotary member in said chamber, curved blades on said member forming buckets adapted to receive liquid which is located in said chamber, and a port adjacent the center of the rotary member for introducing a fluid under pressure into said buckets to expel the liquid therefrom against said blades to impart a torque to said member.

19. In a motor, the combination with a 55 chamber, of a rotary member in said chamber, blades on said member directed in a direction opposite to the direction of rotation of said member, said blades forming buckets adapted to receive a liquid which is 60 located in said chamber, and a port adjacent the center of the rotary member for introducing a fluid under pressure into said buckets to expel the liquid therefrom and against said blades to impart a torque to 65 said member.

In testimony, that I claim the foregoing as my invention, I have signed my name in presence of two witnesses, this 20th day of December, 1904.

LEWIS HALLOCK NASH.
